United States Patent

Des. 238,450
Patented Jan. 13, 1976

238,450

PAPER CASSETTE

Donald A. Robertson, Fairport, and Howard D. Ring,
Rochester, N.Y., assignors to Xerox Corporation, Stamford, Conn.

Filed Apr. 30, 1974, Ser. No. 465,459

Term of patent 14 years

Int. Cl. D16—05

U.S. Cl. D61—1 Q

FIG. 1

FIG. 2

FIG. 3

FIG. 4

FIG. 5

FIG. 6

FIG. 7

FIG. 1 is a perspective view of a paper cassette, showing our new design;

FIG. 2 is a top plan view;

FIG. 3 is a bottom plan view thereof;

FIG. 4 is a left side elevational view;

FIG. 5 is a front elevational view thereof;

FIG. 6 is a right side elevational view; and

FIG. 7 is a rear elevational view.

We claim:

The ornamental design for a paper cassette, as shown and described.
